UNITED STATES PATENT OFFICE.

SAMUEL STEINBERG, OF LAPORTE, INDIANA.

WATCH-BOW.

1,026,061.

Specification of Letters Patent.

Patented May 14, 1912.

Application filed December 27, 1911. Serial No. 668,048.

To all whom it may concern:

Be it known that I, SAMUEL STEINBERG, a citizen of the United States, residing at La-
porte, in the county of Laporte and State of
5 Indiana, have invented certain new and useful
Improvements in Watch-Bows; and I do
hereby declare the following to be a full,
clear, and exact description of the invention,
such as will enable others skilled in the art
10 to which it appertains to make and use the
same.

My invention relates to new and useful
improvements in watch bows and more particu-
larly to means for securing the same in
15 position.

An object of the invention is to provide
means whereby the bow may be securely fast-
ened to the stem of the casing, and another
20 object is to provide means whereby the bow
may be securely held in position without in-
terfering with the winding or setting mech-
anism of the watch.

Other objects and advantages will be here-
inafter more fully made apparent in the
25 specification and pointed out in the claim.

In the accompanying drawings which
form part of this application, Figure 1 is an
enlarged elevational view of the bow secured
30 in position, said view being partly in sec-
tion, while, Fig. 2 is a side view at right an-
gles to Fig. 1.

Referring to the drawings in which simi-
lar reference numerals designate correspond-
35 ing parts throughout the several views, 1
represents the stem of the casing, with the
winding stem 2 projecting from the upper
end thereof, which is preferably thickened
or enlarged at opposite sides, as shown at 3,
40 to receive the opposite ends or ears 4 of the
bow 5, as will be more fully described.

The bow 5 may be of any form desired and
is provided with the hollow ears 4, pre-
viously mentioned, at its opposite ends, said
ears being in alinement with one another
45 and adapted for engagement against the op-
posite thickened portions 3 of the stem 1.
The inner ends of the ears 4 are slightly re-
duced, as shown at 6, and adapted for en-
gagement within the opening 7 provided
50 therefor in the thickened portions 3 of the
stem 1.

Extending inwardly from the center of
each opening 7 is a threaded passage 8 to
accommodate the reduced threaded end 9 of

the securing screw 10, the enlarged smooth 55
portion of which works within the perfo-
rated ear 4. It will be understood that each
ear 4 is hollow from end to end and the
screw 10 may be readily screwed into posi-
tion by any suitable tool (not shown) en- 60
gaged against the slotted end of said screw.

When the screw 10 is in position, with its
threaded portion 9 engaged within the
threaded passage 8, the slotted or outer end
of said screw is some distance inwardly of 65
the outer end of the ear 4 and the screw 10
is prevented from working out of the ear 4
by means of a flat screw or plug 11 engaged
within the outer internally threaded end 12
of said ear. The threads upon the flat screw 70
or plug 11 and those within the outer end
12 of the ear 4 are preferably left-hand
threads, while those upon the reduced
threaded end 9 of the screw 10 and within
the passage 8, are right hand threads. Thus 75
it will be seen that should the screw 10 work
loose the outward movement of the same
would tend to tighten the plug 9 by working
against the inner face of the latter, rather
than loosen the same. 80

The passage 8 within the thickened por-
tion 3 of the stem 1 and the threaded end 9
of the screw 10, are of such length as to ex-
tend only a portion of the way through said
thickened portion and therefore cannot in- 85
terfere with the winding or setting of the
watch.

This form of bow and securing means
may be employed upon the type of watch
stems now in use and will eliminate all dan- 90
ger of the bow becoming detached from the
stem and allowing the watch to drop and
probably cause serious damage to the works.

The screws 10 and 11 may be formed of
any suitable material and the plug 11 is 95
preferably flush with the outer end of the
ear 4 when said plug is in position to close
the outer end of said ear and prevent the
screw 10 from working out of said ear.

What I claim is:

The combination with a watch casing stem
having recesses, and threaded passages ex-
tending inwardly from said recesses; of a
bow having ears with reduced ends for en-
gagement within the recesses, securing 105
screws within the ears and having reduced
threaded ends for engagement within the
threaded passages, and screw plugs having

2
threads directed oppositely to the threads on the reduced ends of the securing screws and engaged in the outer ends of the ears for closing said outer ends and preventing the securing screws from working out of position.

In testimony whereof I have signed my

name to this specification in the presence of two subscribing witnesses.

SAMUEL STEINBERG.
